DESIGN FOR A STOP AND TAIL LIGHT HOUSING FOR AUTOMOBILES

John R. Glocksin and Anton Zucker,
Bay City, Mich.

Application May 3, 1941, Serial No. 100,758

Term of patent 7 years

To all whom it may concern:

Be it known that we, John R. Glocksin and Anton Zucker, both citizens of the United States, and residents of Bay City, in the county of Bay and State of Michigan, have invented a certain new, original, and ornamental Design for Stop and Tail Light Housing for Automobiles, of which the following is a specification, reference being had to the accompanying drawing, forming a part thereof.

In the drawing:

Fig. 1 is a front elevational view of a stop and

tail light housing for automobiles, showing our new design;

Fig. 2 is a top plan view thereof;

Fig. 3 is an end elevational view thereof.

What we claim is:

The ornamental design for a stop and tail light housing for automobiles, as shown.

JOHN R. GLOCKSINE.
ANTON ZUCKER.
